Michael Catania(57) **CLAIM**

The ornamental design for an antenna, as shown and described.

DESCRIPTION

FIG. 1 is a top plan view of an antenna showing our new design together with a base in broken lines;

FIG. 2 is a side elevation view thereof;

FIG. 3 is a front elevation view thereof;

FIG. 4 is bottom plan view thereof;

FIG. 5 is a top perspective view thereof;

FIG. 6 is a top plan view of the antenna without the unclaimed base structure;

FIG. 7 is a front elevation view thereof;

FIG. 8 is a top plan view showing our design in the context of an alternative unclaimed base structure;

FIG. 9 is a side elevation view thereof;

FIG. 10 is a front elevation view thereof;

FIG. 11 is bottom plan view thereof; and,

FIG. 12 is a top perspective view thereof.

The broken lines are for illustrative purposes only and form no part of the claimed design.
